UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPOGRAPHICAL MACHINE.

1,265,344.

Specification of Letters Patent.

Patented May 7, 1918.

Application filed July 28, 1916. Serial No. 111,766.

To all whom it may concern:

Be it known that I, GEORGE P. KINGSBURY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices 15 are released from a magazine in the order in which their characters are to appear in print and then assembled in line, the composed line transferred to the face of a mold, the mold filled with molten metal to form a slug 20 or linotype against the matrices which produce the type characters thereon, and the matrices thereafter returned through distributing mechanism to the magazine from which they started. More particularly, it 25 relates to the distributing mechanism for such machines when equipped with a plurality of magazines, the general principle involved being the preliminary separation of the matrices according to letter and their 30 subsequent separation according to form or font for delivery into the appropriate magazines.

In the accompanying drawings, I have shown my invention merely in preferred 35 form and by way of example and as applied to a linotype machine of the class stated, but obviously many changes and variations may be made therein and in its mode of application which will still be comprised within its 40 spirit. Thus it may be similarly applied to other forms of typographical machines, such as typesetters and the like, which handle type or dies instead of matrices. Generally speaking, I desire it to be understood that I 45 do not limit myself to any specific form or embodiment, except in so far as such limitations are specified in the claims.

Referring to the drawings:

Figure 1 is a vertical section through the 50 upper portion of a linotype machine having my invention applied thereto;

Fig. 2 is a section on the line 2-2 of Fig. 1;

Fig. 3 is a section on the line 3-3 of 55 Fig. 2;

Fig. 4 is a view similar to Fig. 1 showing the parts in different relative positions;

Fig. 5 is a detached perspective detail;

Fig. 6 is a section on the line 6-6 of Fig. 4, looking toward the rear; and

Fig. 7 illustrates the special form of matrices employed.

The matrices X are stored according to form or font in the four vertical channeled magazines A, B, C and D (although a greater or less number may be employed) and are released therefrom in the required order and assembled in line in the customary way. After the slug has been cast, the composed line is carried upward by the second elevator E (see Fig. 6) and pushed endwise by the transfer device E⁸ into the distributor box E¹ wherein the matrices are detached from the line one at a time by the lifting finger E¹¹ and delivered between the threads 70 of the conveying screws E² rotated in the usual way from the driving pulley E⁴. The screws E² (three in number) carry the matrices along the longitudinally grooved distributor bar E³ which releases them at different points in its length, as usual. The parts so far described are or may be of the ordinary construction.

It is pointed out that the matrices of all fonts are caused to traverse the distributor 85 bar E³, which releases them at one point or another according to character and irrespective of form or font, so that other mechanism must be provided to effect the further separation of the released matrices according to individual form or font and their 90 final delivery to the corresponding magazine. It is to this latter mechanism that my present invention is particularly directed, as will now be described.

As the matrices X are released from the distributor bar E³, they drop into a throat or entrance E⁵, divided by partitions E⁶ into a series of channels, one for each of the releasing points of the bar. Interposed between the entrance E⁵ and the matrix magazines is an endless traveling conveyer or carrier F adapted to be operated intermittently and in synchronism with the distributor so as to receive the matrices as they are released therefrom and transport and deliver them to the corresponding magazine. In the present embodiment, the conveyer comprises a series of parallel plates F¹ adapted to move transversely in a closed vertical or- 110

bit and equidistantly spaced apart so that those in the upper horizontal flight will register with those of the lower flight as the carrier is advanced step by step. The plates 5 F^1 are connected together at their opposite ends by links F^2 , each of which is pivotally connected by means of screw studs to the two adjoining plates. It will be noted that the links F^2 have their pivot bearings 10 somewhat enlarged, so as to provide in effect sprocket chains to coöperate with sprocket wheels F^7 whose teeth enter between the enlarged bearings of adjacent links. There 15 are four such sprocket wheels, two at the front and two at the rear, suitably journaled in the framework, and serving to guide and support the conveyer plates as they travel around in their closed orbit. The plates F^1 extend entirely across the machine through- 20 out the width of the magazines and the entrance E^5 , and are formed in their opposite side faces with grooves f , corresponding in number to that of the channels of the individual magazines and the entrance, and the 25 corresponding grooves in the several plates are arranged in the same vertical plane, so that each two adjoining plates will provide in effect a channeled pocket or holder to receive the matrices as they pass from the 30 channels of the entrance E^5 and subsequently deliver them into the corresponding channels of the appropriate magazine. To maintain the plates F^1 in a truly upright position during their travel, each of them is 35 provided at both ends near its upper and lower edges with projecting lips or tongues F^5 adapted to engage in straight horizontal grooves or guideways formed in the inner faces of a pair of plates F^6 fixed to the opposite sides of the machine frame (see particularly Figs. 5 and 6). According to the 40 foregoing construction, as the plates are advanced intermittently through the machine, they present two opposed horizontal flights 45 of open upright channeled pockets traveling in opposite directions, the upper pockets receiving the matrices as they pass from the channel entrance E^5 , and the lower ones carrying the previously distributed matrices 50 across or delivering them into the underlying magazines, each pocket of the series being brought in turn beneath the channel entrance and subsequently presented above each of the four magazines in succession. 55 If, however, the matrices discharged into a given pocket were left therein until it arrived at the magazines, the contained matrices would necessarily become inverted, *i. e.*, with their lower ends uppermost, and 60 consequently they would be discharged into the magazines in an improper position. To avoid this, the pockets constituted by the adjoining plates are left open at both the top and bottom, so that during the travel of 65 the conveyer the matrices discharged into

the pockets of the upper flight may pass therefrom into those of the lower flight, and thus maintain the matrices at all times in an upright or uninverted position. This passage of the matrices through the conveyer 70 is controlled by a fixed transverse plate F^8 supported in the framework between the oppositely traveling flights of pockets, and in position to close the bottom of each pocket as it is brought into operative relation to 75 the channel entrance E^5 . Similarly, there is provided a second fixed plate F^9 arranged below the lower flight of pockets in position to close that one which is located at the time one step in advance of the upper pocket 80 in receiving position. As a result of the above construction, when the matrices are discharged from the entrance E^5 into a pocket of the upper flight in receiving position, they are temporarily retained therein 85 by the plate F^8 , (see Fig. 1), and then when the carrier advances one step forward, the matrices are carried forwardly from across the plate and dropped into the registering pocket of the lower flight, as shown in Fig. 4, 90 wherein they are temporarily retained by the plate F^9 . The next advance of the carrier presents the matrices to the group of magazines, into one or another of which they are discharged according to form or font.

The delivery of the matrices into the magazines is controlled by selecting means which allow them to drop from the conveyer pockets when presented above the corresponding magazine, but which otherwise maintain the 100 matrices within the pockets so that they may be carried farther for presentation to the appropriate magazine. Such means, in the present instance, consist of series of font-selectors a , b and c attached respectively to the magazines A, B and C at their receiving ends, each series having one selector for each channel of the corresponding magazine. The selectors of each magazine are in the form of thin metal strips or members projecting partly across its entrance mouth and lying between the matrix channels and formed at their free ends with laterally projecting lips (see Fig. 3) to coöperate with the descending matrices. The selectors of 110 the several magazines differ relatively as to length so as to vary the location of their laterally projecting lips, which are designed to cooperate with differently located notches in the matrices of the respective fonts. 115

The matrices employed are illustrated in Fig. 7, there being four fonts in all, one for each of the magazines and numbered 1, 2, 3 and 4, respectively. The matrices of fonts 1, 2 and 3 are formed at their lower ends 125 with longitudinally extending notches x^1 , x^2 and x^3 , these notches being located in different relative positions in the respective fonts, as shown. The matrices of font 4 are without such notches. 130

The font distribution will now be clear: As the matrices are carried off the stationary plate F^9 by the traveling conveyer, they are all first located above the magazine A , and if any of such matrices are of font 1 belonging thereto, their notches x^1 register with the laterally projecting lips of the selectors a , which thus release the matrices from the conveyer and allow them to pass immediately into the magazine. If, however, none of the matrices belongs to the magazine A , the selectors a support or maintain them within the pocket of the conveyer, and the latter at its next advance presents them to the second magazine B , where they are subjected to the detecting action of the second series of selectors b . Such of the matrices belonging to this magazine, which contains font 2, will have their notches x^2 registering with the projecting lips of the selectors b and they will therefore be released from the conveyer and allowed to pass into the magazine. At the next advance of the conveyer, the matrices remaining in the pocket are located above the third magazine C , and those belonging thereto (font 3) are released from the pocket by the selectors c , whose projecting lips register with the notches x^3 of the matrices. The matrices (those of font 4) still remaining in the pocket and undistributed into the three previous magazines are then presented above the last magazine D , into which they are instantly dropped, there being no font selectors attached to this magazine. It will be understood, of course, that during the travel of the conveyer, each of its pockets will contain one or more matrices which have fallen from the distributor bar E^8 , and that all of the pockets of the series are presented successively to each of the magazines in turn, the associated font selectors coöperating with the matrices as they are presented momentarily thereto and serving either to permit or prevent their release from the conveyer according to form or font.

The magazines are attached at their upper ends to transverse supporting bars A^1 , B^1 , C^1 and D^1 , which are connected by tongue-and-groove connections to fixed frame members so as to be slid endwise from the machine to effect the independent removal of the magazines, rollers being journaled to said bars and traveling upon fixed tracks to facilitate their sliding movements, the supporting members A^1 , B^1 and C^1 having wide upper faces flush with the upper ends of the magazines serving to maintain the matrices within the pockets of the traveling conveyer as they are carried across the spaces between the adjoining magazines.

As before explained, the channels of the conveyer pockets are constituted by the grooves f formed in the opposing faces of

the plate F^1 , and these grooves are arranged to register with those in the magazines when the matrices are presented thereto, as represented in Fig. 2, the effect being that the matrices are guided solely by their ears in 70 passing from the conveyer into the magazine channels. The grooves f are somewhat enlarged or widened between their opposite ends so that the matrices may be shifted laterally as they pass therefrom to allow their body portions to clear the projecting lips of the font selectors, as clearly represented in Fig. 2. This arrangement avoids the necessity of cutting the font separating notches x^2 of the matrices entirely through their 80 body portions. The use of the grooves f , which allow the matrices to be guided entirely by their projecting ears, is also advantageous in that the matrices are always kept under positive control irrespective of 85 their relative thicknesses. The partitions E^6 of the entrance E^5 are also formed with laterally projecting guiding pieces E^7 to engage the matrix-ears and insure their proper entrance into the grooves f of the conveyer 90 plates F^1 (see Fig. 6).

Any suitable mechanism may be used for imparting to the conveyer F the step by step motion previously described. In the present instance, there is employed for this 95 purpose a pair of arms F^{10} fixed to the opposite ends of a transverse rock shaft F^{12} , and provided at their lower ends with gravitating or spring-pressed pawls F^{11} adapted to engage upstanding noses or projections 100 F^4 formed on short connecting plates F^3 between each adjoining pair of the sprocket links F^2 before described, see particularly Figs. 5 and 6. Attached to one end of the rock shaft F^{12} is a shorter depending arm 105 F^{15} arranged to be engaged by a roller F^{14} journaled on the end of the lower distributor screw E^2 . A spring F^{16} attached to the rock shaft through the medium of a crank arm F^{17} , and pulling from a fixed part of the 110 machine, serves to hold the arm F^{15} in engagement with the roller F^{14} at all times. As a result of this construction, the arms F^{10} are caused to swing to and fro at each rotation of the distributor screws, the pawls F^{11} 115 when the arms are in their innermost position being arranged to engage the projections F^4 of the conveyer chains and by such engagement acting, when the arms are swung outwardly, to advance the carrier one step 120 forwardly to an extent equal to the distance between two adjoining pockets. In other words, the conveyer is advanced intermittently so as to present a new pocket beneath the channelled entrance E^5 at each rotation 125 of the distributor screws. Preferably, the parts are so timed that the conveyer pockets are brought into receiving position at or just prior to the period when the matrices are released from the distributor bar E^8 . The 130

conveyer will, of course, remain in a position of rest during the period taken up by the return of the operating arms F¹⁰ and until they are again moved outward by the 5 continued rotation of the distributor screw. This temporary interruption of the movement of the conveyer affords ample time for the matrices to drop from its pockets into the magazines.

10 As before stated, I have shown my invention merely in preferred form and by way of example, and it will be obvious that many of the details may be widely varied in form or arrangement without materially changing 15 their mode of action or the results secured by the general organization. Such modifications or alterations will readily suggest themselves to those skilled in the art without departure from its scope.

20 Having thus described my invention, its construction and mode of operation, what I claim and desire to secure by Letters Patent of the United States is as follows:

1. Typographical distributing mechanism 25 including a matrix conveyer comprising an endless series of pockets traveling in opposed immediately adjacent flights, the pockets of the two flights being arranged to communicate in the operation of the conveyer 30 so as to permit the matrices to pass through the pockets of one flight into those of the other to avoid their inversion.

2. Typographical distributing mechanism 35 including a matrix conveyer comprising an endless series of pockets traveling in opposed overlying flights, the said conveyer having its pockets open at both the top and bottom and relatively arranged so that those of the upper flight will register with those 40 of the lower flight in the course of travel of the conveyer, for the purpose described.

3. Typographical distributing mechanism 45 including a matrix conveyer comprising an endless series of pockets traveling in opposed overlying flights, the said conveyer having its pockets open at both the top and bottom and relatively arranged so that those of the upper flight will register with those of the lower flight in the course of travel of the conveyer to permit the passage of the 50 matrices through the former into the latter, and means for controlling such passage of the matrices.

4. Typographical distributing mechanism 55 including a matrix conveyer comprising an endless series of pockets traveling in opposed immediately adjacent overlying flights, the pockets of the two flights being arranged to communicate in the operation of the conveyer so as to permit the matrices to pass 60 through the pockets of the upper flight into those of the lower to avoid their inversion, and means for releasing the matrices from the lower flight of pockets at different points 65 according to form.

5. Typographical distributing mechanism including a matrix conveyer comprising an endless series of pockets traveling in opposed overlying flights, the said conveyer having its pockets open at both the top and 70 bottom and relatively arranged so that those of the upper flight will register with those of the lower flight in the course of travel of the conveyer to permit the matrices to pass through the former into the latter, and 75 means for releasing the matrices from the lower flight of pockets at different points according to form.

6. In a typographical machine, the combination of a plurality of magazines containing 80 matrices of different forms or fonts, a distributor to separate the matrices according to character irrespective of form, an intermediate traveling conveyer comprising a series of pockets to receive the matrices so 85 separated and present them to the several magazines successively, and matrix selecting means associated with each of the magazines to control the delivery thereinto of the matrices of corresponding form. 90

7. In a typographical machine, the combination of a plurality of channeled magazines containing matrices of different forms or fonts, a distributor to separate the matrices according to character irrespective of 95 form, an intermediate traveling conveyer comprising a series of channeled pockets to receive the matrices so separated and present them to the several magazines successively, and a series of matrix selectors 100 associated with each of the magazines and corresponding in number to that of the channels thereof to control the delivery thereinto of the appropriate matrices.

8. In a typographical machine, comprising 105 matrices differing in form, the combination of a distributor to separate the matrices according to character irrespective of form, an underlying conveyer comprising a series 110 of pockets to receive the matrices so separated, and a plurality of selectors varying in form and arranged at different points in the travel of the conveyer, the said selectors adapted to coöperate with the matrices in the conveyer and control their release therefrom at one point or another according to form. 115

9. In a typographical machine comprising 120 matrices each formed with a notch at its lower end, the said notches varying in location in the respective matrices, the combination of a distributor to separate the matrices according to character irrespective of form, a conveyer comprising a series of pockets to receive the matrices so separated, and a plurality of matrix selectors arranged 125 at different points in the travel of the conveyer, the said selectors being formed respectively with projecting lips differently located to correspond with the location of 130

the matrix notches to control the release of the matrices from the conveyer at one point or another according to form.

10. In a typographical machine, the combination of a plurality of channeled magazines containing matrices of different forms or fonts, a distributor to separate the matrices according to character irrespective of form, a conveyer comprising an endless series of channeled pockets traveling in opposed overlying flights and constructed and arranged so that those of the upper flight will receive the separated matrices and subsequently discharge them into those of the lower flight, and a series of individual selectors for each of the magazines to coöperate with the matrices in the lower flight of pockets and control their delivery into the appropriate magazine.

20. 11. In a typographical machine, the combination of a plurality of channeled magazines containing matrices of different forms or fonts, a distributor to separate the matrices according to character irrespective of form, an intermediate conveyer comprising an endless series of channeled pockets traveling in opposed overlying flights, the said pockets being open at both the top and bottom and arranged so that 30 the matrices will pass into those of the upper flight and subsequently be discharged into those of the lower flight, and a series of selectors associated with each of the magazines and arranged to retain the matrices in 35 the lower flight of pockets until they have reached their appropriate magazine.

12. A channeled magazine provided with a series of matrix selectors, one for each channel, the said selectors being in the form of thin metal strips projecting partly 40 across the entrance mouth of the magazine and lying between the matrix channels and formed with laterally projecting lips to coöperate with the matrices as they enter the 45 magazine.

13. A channeled magazine provided at its receiving end with a series of like matrix selectors, one for each channel.

14. In a typographical machine, the combination of a plurality of channeled magazines containing matrices of different forms or fonts, a distributor to separate the matrices according to character irrespective of form, and an intermediate traveling conveyer to receive the matrices so separated and deliver them to one or another of the magazines according to form, the said conveyer comprising a connected series of 55 grooved plates providing between them channeled pockets for the matrices.

15. In a typographical machine, the combination of a plurality of channeled magazines containing matrices of different forms or fonts, a distributor to separate the 65 matrices according to character irrespective

of form, and an intermediate traveling conveyer to receive the matrices so separated and deliver them to one or another of the magazines according to form, the said conveyer comprising a connected series of 70 plates each formed in its opposite side faces with grooves, which thus provide a plurality of matrix channels between each two adjoining plates of the series.

16. In a typographical machine, the combination of a plurality of channeled magazines containing matrices of different forms or fonts, a distributor to separate the matrices according to character irrespective of form, and an intermediate traveling conveyer to receive the matrices so separated and deliver them to one or another of the magazines according to form, the said conveyer comprising an endless series of 75 grooved plates moving in opposed overlying flights and equidistantly spaced apart so that the grooves of the upper flight will register with those of the lower flight in the course of travel of the conveyer, for the purpose described. 80

17. In a typographical machine, the combination of a plurality of channeled magazines containing matrices of different forms or fonts, a distributor to separate the matrices according to character irrespective 95 of form, an intermediate traveling conveyer to receive the matrices so separated and deliver them to one or another of the magazines according to form and comprising a connected series of transverse plates 100 providing matrix carrying pockets between them, and means for maintaining the plates in parallelism in the course of travel of the conveyer.

18. In a typographical machine, the combination of a plurality of channeled magazines containing matrices of different forms or fonts, a distributor to separate the matrices according to character irrespective of form, an intermediate traveling conveyer to 105 receive the matrices so separated and deliver them to one or another of the magazines according to form and comprising an endless series of transverse plates moving in opposed overlying flights and providing matrix carrying pockets between them, and means for maintaining the plates in parallelism as they move in their opposed flights. 110

19. Typographical distributing mechanism including a matrix conveyer comprising an endless series of matrix-holding pockets traveling in opposed flights, the said pockets being made up of a train of transversely movable grooved plates each formed at its opposite ends with projecting lips or 115 tongues, and a relatively fixed frame member formed with grooves wherein said tongues engage during the travel of the conveyer, whereby its grooved plates are 120 maintained in proper parallelism. 125

20. Typographical distributing mechanism including a traveling matrix conveyer comprising a connected series of grooved plates providing between them channeled 5 pockets for the matrices, and the grooves in said plates being enlarged between their ends to permit the lateral shifting of the matrices, for the purpose described.

21. In a typographical machine, the combination of a plurality of magazines containing matrices of different forms or fonts, a distributer to separate the matrices according to character irrespective of form, an intermediate conveyer comprising a series of channeled pockets to receive the separated matrices and deliver them to one or another of the magazines according to form, and means for advancing the conveyer step by step to locate each of its matrix-holding 20 pockets in operative relation to the several magazines in succession.

22. In a typographical machine, the combination of a plurality of magazines containing matrices of different forms or fonts, a distributer to separate the matrices according to character irrespective of form, an intermediate conveyer comprising an endless series of channeled pockets traveling in opposed overlying flights, the pockets of the 30 upper flight being arranged to receive the matrices when separated by the distributer, and those of the lower flight arranged to discharge the matrices into the magazines, and means for advancing the conveyer step 35 by step to present different pockets to the distributer and to each of the magazines, respectively.

23. In a typographical machine, the combination of a plurality of magazines containing matrices of different forms or fonts, a distributer to separate the matrices according to character irrespective of form, an intermediate conveyer comprising an endless series of channeled pockets traveling 40 in opposed overlying flights, the pockets of the upper flight being arranged to receive the matrices when separated by the dis-

tributer, and those of the lower flight arranged to discharge the matrices into the magazines, and means for advancing the 50 conveyer step by step to present different pockets to the distributer and to each of the magazines respectively, the said means being operated in synchronism with the distributer so as to bring a different pocket into 55 receiving relation thereto at each release of matrices therefrom.

24. In a typographical machine, the combination of a plurality of channeled magazines containing matrices of different forms 60 or fonts, a distributer to separate the matrices according to character irrespective of form, and an intermediate traveling conveyer to receive the matrices so separated and deliver them to one or another of the 65 magazines according to form, the said conveyer comprising a series of channeled pockets in which the matrices are carried.

25. In a typographical machine, the combination of a plurality of magazines containing matrices of different forms or fonts, a distributer to separate the matrices according to character irrespective of form, a traveling conveyer to receive the matrices so separated and carry them across the entrance mouths of the magazines, and relatively fixed means to support the matrices in the conveyer until they reach their appropriate magazine.

26. In a typographical machine, the combination of a plurality of magazines containing matrices of different forms or fonts, a distributer to separate the matrices according to character irrespective of form, means for presenting the matrices so separated to the magazines successively, and fixed selectors located at or across the receiving ends of the magazines to control the delivery thereinto of matrices of corresponding form.

In testimony whereof, I have affixed my signature.

GEORGE P. KINGSBURY.
